DELPHIA, PENNSYLVANIA, A CORPORATION OF PENNSYLVANIA

TOY GUN

Application filed July 2, 1930. Serial No. 465,378.

This invention relates to a toy gun. It has to do, more particularly, with a miniature field piece that is modeled along the lines of a modern artillery cannon and is very similar in 5 appearance thereto. More specifically, this invention relates to a gun toy constructed for the enjoyment and pleasure of children that is designed to forcibly eject spherical pellets or other and similar projectile devices.

10 In the past, toy gun structures have been of such form and have embodied such operating mechanism as to give rise to numerous difficulties in the operation thereof. Furthermore, these guns have not been easily operated by children primarily because the ejecting mechanism was under the influence of a heavy tension spring that was often of such tensile strength as to defeat the childish efforts to depress it. Likewise, various parts 15

20 making up the internal mechanism of the gun were ill-shaped and were not fitted together with any great degree of precision which permitted of the binding and jamming of such mechanism at various stages in the operation thereof.

25 A still further drawback to these prior art devices resided in the fact that, in the main, such parts as the barrel, wheels, trail and operating mechanism were made up of cast material which is not only expensive but is also subject to breakage under the usual hard knocks which these devices receive when in the hands of children. Furthermore, as an added disadvantage, these miniature field 30

35 pieces were provided with a fixed barrel whose muzzle could not be adjusted vertically to vary the range of the projectile.

One object of this invention is to provide a 40 miniature field piece, simulating the modern artillery gun, which is of simple, durable and substantial construction, and one that can be easily manipulated by a child.

Another object of this invention lies in the 45 provision of a toy gun of very rugged construction that is made up of a minimum of parts that may be easily manufactured of a metal stamped and bent to proper form and readily assembled at a minimum cost and in a minimum of time.

50 Still another object of this invention is to

provide a novel and useful toy which shall be enjoyable, interesting and instructive to children and others and that will readily withstand the rough usage to which gun toys of this type are usually subjected.

55

A still further object of this invention is to provide a miniature field piece, very similar in appearance to the modern artillery gun that will be extremely efficient in operation and will not readily be disabled by hard 60 usage.

Still another object of this invention is to provide a toy gun equipped with a projectile feed which permits of the ready introduction of spherical pellets into the ejecting chamber 65 without danger of the pellets becoming wedged in the feed passage or operating mechanism and thus rendering the gun inoperative.

Still another object of this invention is to provide a toy artillery cannon provided with an adjustable muzzle that may be raised or lowered and locked in the position to which it is adjusted, this feature of raising and lowering the muzzle permitting of a variance 70 in the range of the projectile which has not hitherto been found in miniature guns.

75 This invention contemplates the provision of a toy cannon, the general design of which follows very closely the design of a modern 80 artillery field piece. Such members as the wheels, the trail, the muzzle and recoil cylinder substantially simulate the corresponding parts of a standard field piece. However, these external parts of the gun are preferably constructed of a light yet durable stock and may be easily and readily bent to the proper proportion, the construction being such as to greatly lessen the cost of manufacture and produce a much improved toy 85 gun.

90 The internal mechanism is made up of a light, durable stock that may be easily and readily bent to the proper contour. This inner mechanism is adapted to eject miniature projectiles that are automatically fed to an ejecting chamber through a conduit that has the discharge end thereof closed by the ejecting plunger. This ejecting plunger is 95 spring-actuated and the barrel in which it is 100

located is so disposed that when the feed channel is uncovered by the ejecting plunger, the spherical projectiles will move to a position of contact with the face of the 5 plunger and will remain in contact therewith during a certain phase of the operation of cocking the gun.

Furthermore, this invention contemplates the provision of a cocking lever which is 10 mounted on the main supporting axle of the toy cannon. This axle is utilized as a pivot rod for the cocking lever as well as a pivot rod for the barrel of the gun. Both the cocking lever and the pivot rod may be pivotally 15 moved about the axle and means is provided for governing the position to which the cocking lever and barrel may be adjusted. Adjustment of the barrel will either elevate or 20 depress the muzzle to permit a variation in the projectile range.

The mechanism for operating the plunger of this toy gun is of novel design and is adapted to operate with a high degree of efficiency with a minimum of moving parts. 25 In the construction of these parts, much attention has been given to the accurate formation thereof to obviate any rough spots, and disadvantageously located seams that might hinder the efficient coordination of the 30 moving parts or prevent the ready passage of the spherical pellets therethrough.

Many other objects and features of this invention will be noted in the accompanying drawings and the written description 35 wherein similar characters of reference designate corresponding parts and wherein:

Figure 1 is a perspective view of the preferred form of miniature field piece with certain of the parts broken away to more 40 clearly illustrate the internal mechanism of this device.

Figure 2 is a longitudinal section taken along the vertical center line of the gun showing the position of the operating mechanism prior to operation thereof. 45

Figure 3 is a fragmentary view of the rear sections of the breech showing the relative position of the operating parts just prior to the ejecting operation. 50

Figure 4 is a side elevation with one wheel removed.

Figure 5 is a top plan view of the gun shown in Figure 1.

Figure 6 is a rear elevation, partly broken away, of my gun.

Figure 7 is a perspective view of the barrel and recoil cylinder removed.

Figure 8 is a perspective view of the inner 60 barrel and projectile magazine.

Figure 9 is a perspective view of the ejecting plunger removed from the gun.

Figure 10 is a perspective view of the plunger operating sleeve.

65 Figure 11 is a perspective view of the plunger operating sleeve, with the plunger mounted thereon.

Figure 12 is a perspective view of the cradle for supporting the barrel and dummy recoil cylinder.

Figure 13 is a perspective view of the operating lever and associated mechanism removed from the gun.

Figure 14 is a perspective view of the trail.

In the drawings, with particular reference to Figures 1, 5 and 6, the main structure for the support of this gun is shown as comprising, an axle 1 on which is mounted the oppositely disposed wheels 2. A trail 3, hereinafter referred to, is also mounted, at one end, by means of ears 9, on the axle 1 the opposing end thereof resting on the floor or other support surface. The axle 1 is preferably of hollow tubular construction and the wheels mounted thereon, Figure 6, are of pressed steel formed into a disk having curled tread as at 4 that are concentric with the tubular axle.

Each wheel is provided with a drawn steel hub 5 that is somewhat elongated in longitudinal cross section to provide a widely separated bearing surface on the axle 1. Lateral movement of these wheels on the tubular axle is negligible owing to the fact that the opposing ends of the axle are flattened as at 6 and washers 7 are interposed intermediate such flattened portion and the exterior annular face of each hub. The interior face of each hub abuts against the ears 9 comprising the inner end of trail member 3.

The provision of widely separated bearing surfaces for the wheels of this toy gun practically eliminates any tendency of the wheels to wobble and the method of securing these wheels on the axle is a substantial advance over that type of gun equipped with a wooden axle provided with cotter keys located in openings at the opposing ends thereof. This prior type of axle just mentioned, increases the overall length of the axle and consequently, the size of the cartons required for shipping of such guns must be of sufficient width to accommodate them. With this present invention, the length of the axle is materially reduced and consequently the cartons necessary for the shipment thereof may be of lesser width.

The trail member 3, Figures 5, 6 and 14, is adapted to be pivotally mounted on the axle 1 by means of the ears 9 that are each drilled centrally as at 10 to produce aligning openings through which the axle 1 extends. More specifically, this trail member is preferably made up of pressed sheet metal, substantially trapezoidal in plan view, and is provided with flanged cross members 11 progressively longer from the butt end towards the ears 9. The intervening spaces 12 between the transverse cross members 10 are substantially rectangular in appearance.

Located at the lowermost end of the trapezoidal trail member is a spade piece 13 that may be integrally formed thereon and is bent over into a U as at 14 at the lowermost end thereof. The design of this spade is not necessarily limited to that shown, likewise, the trail member may be of any design suitable for the support of the gun. By providing the spade with a U shaped end, the possibility of marring or scratching the surface on which the gun may rest is precluded.

In the support of the barrel and recoil cylinder, I have provided a one piece cradle 28 shown best in Figures 6 and 12, that preferably take the form of a substantially U shaped member having opposing upstanding arms 15, the lowermost end thereof being substantially vertical as at 16, and drilled as at 17 to provide aligning openings through which the axle 1 may extend, the vertical ends lying intermediate and abutting against the ears 9, Figure 6, of the trail. The lowermost end of each vertical section 16 is joined by a transverse flat piece of stock 18 formed integrally therewith which normally lies below the axle when the cradle member is mounted thereon. The uppermost ends of the arms 15 are provided with enlarged perforated ears 19 that are bent to substantially the outer curvature of the combined outer barrel and the dummy recoil cylinder that will be hereinafter described more in detail. These portions 16 are adapted to fit snugly against the barrel of the gun and to embrace it in such a manner as to rigidly support it on the axle. Furthermore, each of the portions 16 respectively are provided with transversely aligning openings 20 adapted to receive the barrel supporting bolts 21 that pass entirely through the outer gun barrel as will be hereinafter noted.

The combined barrel member and dummy recoil cylinder, designated by the numerals 22 and 23 respectively, Figure 7, are preferably of two part construction and are made up of a light metal which facilitates the ready assembly of these two members. For the purposes of illustration these two parts will be referred to as the right and left hand sides which may be brought into cooperation when mounted in the cradle. In order to properly support this barrel member and dummy recoil cylinder, the bolts 21, hereinafter mentioned, are adapted to extend through the openings 20 of the cradle member and complementary aligning openings 24 in the barrel member that are located adjacent the central portions thereof longitudinally of the barrel, and at points advantageously selected to preclude the possibility of interference with the operating mechanism. In the instance of the lower bolt 21, it has been found advantageous to provide it with a covering of resilient material for a purpose to be hereinafter described.

The particular design of this barrel member is not limited to that shown wherein the barrel is provided with distinct sections of increased diameter. If desired, the diameter of this barrel could be progressively and gradually increased from the muzzle rearwardly toward the breach. The muzzle 25 is substantially flared as shown an annular groove 8 being formed on the inner circumference thereof. The rearmost end is open and is adapted to be covered by a removable cap 26, Figure 7, equipped with a centrally located extension 27 which, in this instance, will offer a surface readily grasped by the fingers of the hand for the removal thereof to obtain access to those elements of the ejecting member located in this section of the barrel. Furthermore, the cap is provided with a semi-circular cut-away portion, as at 51 that is adapted to cooperate with a complementary cut-away portion in the upper side of the barrel end for a purpose to be hereinafter mentioned.

In addition, the dummy recoil cylinder 23 which is closed at the rearmost end, is open at the foremost end and is provided with a cap 29 adapted to enclose such end. This cap is further provided with a hook 30 mounted centrally of the inner side thereof which is adapted to receive one end of a retractile spring 31 hereinafter described more in detail in connection with the operating mechanism.

It can readily be seen that the method of mounting the barrel and dummy recoil cylinder on the axle will permit of the pivoting thereof about such axle for the purpose of elevating and depressing the muzzle. I have provided a means for adjustably regulating the degree to which this muzzle may be tilted, such means serving to rigidly support the posterior section of the barrel when the selected position of adjustment has been determined.

The mechanism for elevating and depressing the barrel of this toy gun is best shown in Figures 1 and 2 wherein it is illustrated as comprising a thumb nut 34 having a centrally located threaded stem 35 extending downwardly from one face thereof and an upwardly extending stem 38 located centrally of the opposing face thereof. The threaded stem 35 is threaded into an internal threaded portion of the tubular sleeve 35', pivotally mounted on the trail 3 by means of lugs 34', journalled in the opposing ears 37 mounted on such trail. The stem 38 extending upwardly from the opposing face of the thumb nut is provided with a section of substantially reduced diameter 39 that is located in an opening 40 formed in the under side of the portion 27 and the cap 26. The portion of reduced diameter of the stem 38 is flattened as at 41 to prevent the withdrawal of the stem from the opening.

It will be readily apparent that rotation of the thumb nut 34 will operate to either raise or depress the muzzle of the gun, the pivotal mounting of the sleeve 35 permitting of such adjustment. This mechanism for adjusting the barrel to various heights will also serve to rigidly support the barrel when the selected position of adjustment has been determined.

The ejecting mechanism of this toy gun is preferably mounted within the barrel, hereinbefore described, and is best shown in Figures 1, 2, 8, 9 and 10. This ejecting mechanism is made up of several distinct and separate elements that are all formed with necessary precision and are fitted together in such a manner as to produce the harmonious cooperation thereof during operation.

In discussing this ejecting mechanism, it will be best to refer to each separate element, with a brief description of the nature and formation thereof with a subsequent description directed to the function of these various elements when mounted in assembled relation.

With reference to Figure 8, I have shown the inner barrel which is designated by the numeral 43 as comprising a substantially tubular member of uniform diameter throughout, having a magazine 44 formed integrally therewith and extending upwardly from the posterior section thereof. This inner barrel when mounted in the outer barrel, has its axis inclined in a vertical upward plane toward the muzzle and relative to the axis of the outer barrel. The plunger and the spring for operating this plunger are adapted to be mounted in the posterior section of this tubular barrel as will be hereinafter described. The projectile magazine 44 is preferably circular in cross section having arcuate ends joined by a substantially straight intermediate portion, the axis of the intermediate portion being disposed in a vertical plane and sloping forwardly and downwardly at an acute angle relative to the axis of the inner barrel. The bore of this magazine presents a storage space for projectiles which are successively fed to the ejecting mechanism.

The charging end 46 of this magazine is preferably flared to allow the ready introduction of spherical pellets thereinto. These pellets, Figure 2, after entering the charging opening 46 are conducted by means of the angling channel 47 to the discharge end 48 which allows an uninterrupted and unrestricted passage of the spheres to a position within the barrel suitable for ejecting.

In the formation of this barrel, and integral magazine, a substantially trident-shaped blank is bent to a circular section with its seam, as at 49, along the top edge of the inner barrel. Prior to the bending of this barrel into some circular section, the laterals which go to make up the magazine channel are first

formed into semi-circular sections. Hence, when the barrel is bent into tubular form these semi-circular laterals cooperate to form the substantially tubular magazine for storing and conducting projectiles, the seam lying along the top side of the magazine, during the formation of the magazine, ears as at 50, are provided which may be subsequently welded.

More specifically, the inner barrel and projectile magazine are formed from one piece of sheet metal blanked out substantially in trident form i. e., as a straight strip of sheet metal to form the barrel and rear extension thereof and having two symmetrically disposed lateral projections, one on each side, each to form one-half of the projectile magazine, the whole being pressed so that the lateral arms form semi-circular troughs which, when the straight barrel length is formed around through three hundred and sixty degrees, constitute substantially a curved tubular magazine integral with the barrel.

The integral construction of the inner barrel 43 and the magazine 44 eliminates any joints or rough edges at the juncture of the magazine with the barrel which is quite an advance over prior structures wherein the magazine and inner barrel were of two-part construction usually welded together. Furthermore, by forming the magazine so that the seam occurs along the top side produces a surface over which the pellets pass that is relatively smooth and free from any joint that might obstruct the passage thereof.

The charging end of the magazine 44 is located in a circular opening 51 formed near the breech end of the outer barrel 22 and on its top side. The opening 51 is made up of two semi-circular openings one of which is formed in the barrel 22 and one of which is formed in the cap 26. It can readily be seen that mounting of the cap on the barrel 22 will bring these two openings into cooperation. Cooperation of these semi-circular openings will clamp the charging end of the magazine 44 in projectile receiving position.

The rearmost end of the barrel 43 extending beyond the junction of the magazine with such barrel is provided to form a guide for the ejecting plunger that is mounted therein and to form a housing for partially enclosing one end of the ejecting spring. A gap 56 is occasioned by a lack of stock in the blank immediately in rear of the magazine 44 although this gap is not necessarily important and is merely provided to reduce the friction between the plunger and the inner wall of the barrel. The under side of this rear section of the barrel is longitudinally slotted as at 57, for a portion of its length for a purpose to be hereinafter described.

Partially enclosing that section of the barrel directly in front of the magazine 44 is the foremost end 59 of a sleeve 58 axially movable on such barrel and adapted to par-

tially enclose the posterior section of such barrel. This sleeve 59 is preferably formed of a flat piece of stock that is bent into circular section with its seam along the bottom edge. As it will be noted, the posterior section of the sleeve 58 is cut away along the longitudinal horizontal center line so that, the sleeve may be moved axially on the barrel 43 without intercepting the magazine 44, that portion of the sleeve beneath the cut-away portion directly underlying such magazine and being adapted to reciprocate therebelow.

This sleeve, is adapted to be operatively connected to a plunger 64 and in accomplishing this, I have provided the longitudinal depending flanges 60 that are formed on the under side of the posterior section of the sleeve, and when this portion of the blank is bent into semi-circular cross section, these flanges depend downwardly therefrom. These flanges are separated by a gap 61 and are provided with the openings 65 adapted to receive rivets that extend through a longitudinal extension 66 formed as a part of the plunger 64 and normally adapted to lie within the gap 61 intermediate the ears 60 as will be hereinafter described more in detail.

The top edge of the sleeve 58 adjacent the end portion 59, is provided with the upstanding sear lug 62 that may be welded thereon and is adapted to be contacted with by a sear, hereinafter referred to, to produce axial movement of the sleeve on the barrel 43 in one direction. Movement in the opposing direction is produced by a coil spring, hereinafter described, such movement being limited by contact between a stop 67 stamped in the under surface of the sleeve 58 and bent to a substantially perpendicular position with relation thereto, and one of the bolts 21, Figure 2, that is provided with a rubber sleeve for absorbing the shock.

As hereinbefore mentioned, the ejecting sleeve 58 is adapted to be operatively connected to an ejecting plunger 64 that normally reciprocates within the posterior section of the interior barrel 43. The specific form of this plunger is best shown in Figure 9 as comprising a longitudinal body portion having one end face made up of segmental sections of metal 68 bent inwardly toward the center to form an impact face. Heretofore, the ejecting plunger was usually made of a cast metal that was solid throughout or consisted of a wooden plug. The cast metal was not the most desirable form of plunger in that the repeated impact of such plunger on the projectiles often served to chip and crack the metal. Furthermore, a wooden plunger would often become grooved, or the impacting face would be indented by repeated impact with the spherical pellets which would ultimately reduce the force with which the plunger contacted with the pellets. The length of spring provided for the actuation

thereof was also relatively short, and as a result was quite powerful to produce the ejecting movement of the plunger. This type of spring often, was of such tensile strength as to preclude childish efforts to depress it.

It will be noted that, in the form of ejecting plunger that I have provided, the impact face is produced by cutting the metal forming such face into triangular segments as at 68 and bending such segments inwardly toward one another until a closure for the end of this tubular plunger has been formed. In assembling the plunger and sleeve, the plunger 64 is mounted in the barrel 43 with the impact face thereof toward the muzzle. The flanges 66 thereof are adapted to extend through the longitudinal slot 57 in the barrel 43 and are guided thereby during reciprocation of the plunger. Reciprocation is produced through the medium of the sleeve 58 that is mounted on the barrel and riveted to the flanges 66 by means of rivets extending through the opening 65 in the depending flanges 60 and complementary openings in the flanges 66. This arrangement, provides a plunger that is located within the barrel and a sleeve that encloses such barrel, as at 59, which will allow free longitudinal movement with respect to the barrel but will preclude any side motion, or end movement of either the sleeve or plunger, which might cause binding.

The rearmost end of the plunger 64 is open and an elongated coil spring 70 is adapted to lie within such plunger, one end thereof abutting against the inner side of the impact face, and the opposing end thereof lying within the extreme posterior section of the barrel 43 and abutting against the vertical end wall, Figure 2, of the dummy recoil cylinder. The operation of the plunger and associated parts, hereinbefore mentioned, will be hereinafter referred to in connection with a detailed description of the operation of this device.

The combined operating lever and cocking bracket designated generally by the numeral 71, is bent as shown in Figures 1, 4, 5 and 13. The cocking bracket is preferably formed from flat stock bent to a substantial U-shape as shown best in Figure 13. More specifically, the operating lever preferably comprises an arm 72 that is rigidly secured, at one end, to one of the upstanding legs 73 of that section of the cocking bracket that is adapted to be mounted on the tubular axle 5, the axle passing through aligning openings 74 formed in each respective leg. These legs are joined by transverse section of stock 75 that is formed integrally therewith and serves as a means for bracing these legs when the bracket is mounted on the axle, the legs lying intermediate and abutting against the legs 14 of the barrel supporting bracket, Figure 8. Furthermore, such construction and

assembly materially reduces lateral play or wobble of the lever 71.

One of the legs 73 of the cocking bracket is provided with a horizontal extension 76 that is bent at right angles thereto and extends in parallelism with the transverse bracing section 75. The outer end of the extension 76 is turned upwardly as at 77 and is substantially triangular in form, an opening 78 being drilled through the apex thereof for the reception of one end of the retractile spring mounted in the dummy recoil cylinder as will be hereinafter explained. Mounted intermediate the ends of the extension 76 is the sear support 79 that extends vertically upward for the greater portion of its length and is bent inwardly as at 80, and then upwardly as at 81, to form a substantially vertical end portion that is drilled centrally as at 82 for the reception of the sear pivot pin 83 carrying the sear 84 thereon.

In mounting this cocking bracket on the axle 5, the triangular extension 77 is adapted to extend upwardly into the combined barrel and dummy recoil cylinder through a longitudinal slot 85 formed in the under side of the dummy recoil cylinder 23, Figure 1. At this time, the upper end of this triangular extension should be in such position as to receive one end of the spring mounted in the dummy recoil cylinder. The sear supporting arm 79 extends upwardly into the barrel 22 through a longitudinal slot 87 formed at approximately the juncture of the dummy recoil cylinder of the barrel 22. With reference to Figure 1 it will be noted that the vertical section of the sear supporting lever 79 lies intermediate the inner wall of the combined barrel and dummy recoil cylinder and the inner barrel 43 so that movement thereof from cocking to released position is entirely free of interception with either of these two last named parts. The upper curved section 80 of the lever 79 follows the arc of the barrel so as to position the upper end 81 of the sear support along the vertical longitudinal center line of the barrel.

The sear 84, which is pivotally mounted by means of a pin 83 on the upper end of its support is preferably provided with a hook-shaped end 90 adapted for positive engagement with the upstanding sear lugs 62 mounted on the sleeve 58. This sear is under the influence of a spring 91 which tends to exert a continuous force on such sear to maintain the hook-like end in engagement with the sear lugs. The posterior end of the sear is turned upwardly as at 93 to produce an end that lies in a plane somewhat above the general plane of the body portion of the sear. This end of the sear, at all times, rides against either the inclined portion 94 of a ramp or the substantially horizontal section 95 thereof which is attached to the under side of the magazine at one end, and rests on the ex-

terior surface of the tubular channel 44, at the other end. Thus movement of the lever 72 downwardly, ultimately brings the rear-most end of the sear into contact with the inclined ramp to depress such end of the sear and raise the opposing hook-like end from engagement with the sear lug.

It will be noted, that the axle of this toy cannon is utilized as a pivot rod for the cocking lever as well as a pivot rod for the combined barrel and dummy recoil cylinder that are mounted thereon by means of the bracket 16. It will be readily apparent that the combined muzzle and dummy recoil cylinder, ejecting mechanism mounted therein, and the cocking lever and associated parts can all be moved in an arcuate path around the axle without disturbing positional relation between any of the elements just named. Furthermore, the operation of the ejecting mechanism may take place regardless of the angle to which the muzzle is tilted. Hence, the provision of an apparatus for elevating and depressing the barrel can be readily incorporated in this structure to vary the tilt of the barrel.

In the operation of this device, I will first refer to Figure 2 which discloses the positional relation of the various elements of this gun when it is in uncocked position and with the barrel tilted upwardly at a slight angle, although the position of adjustment of the exterior combined barrel and dummy recoil cylinder is substantially horizontal. It will be understood, that the thumb nut 34 may be rotated in either direction to vary the cant of the combined barrel and dummy recoil cylinder and resultantly the inner barrel. It is very advantageous, that the inner barrel be inclined toward the rear when the dummy recoil cylinder and integral barrel are substantially horizontal in order that the spherical pellets issuing from the discharge end 48 of the passage 47, will roll by gravity toward the rear of the inner barrel and thus into engagement with the impact face of the ejecting plunger.

With the parts in position shown in Figure 2, the sleeve 58 and the plunger 64 are forward to the limit of their movement with the hook-like end of the sear 84 engaged with the sear lugs 62 of the sleeve. At this time, the rear section of the cocking lever 72 extending rearwardly along the side of the barrel assumes a substantially horizontal position. The recoil spring 31 attached to the triangular extension 77 on the cocking bracket operates to maintain the cocking lever and the sear in the positions just described, of course, it being understood that the sear is maintained in engagement with the sear lugs 62 by the torsion spring 91.

The limit of forward movement of the plunger is limited by the extent to which the ejecting sleeve is allowed to move forward.

Preferably, this movement should be great enough to allow the forward end of the plunger to pass beyond the discharge end 48 of the magazine. With the plunger in this position, the spherical pellets are precluded from entering the barrel. The spring 70 mounted within the plunger and the inner barrel is also effective to aid the spring 31 in maintaining the ejecting mechanism in the position shown since the force exerted on the forward face of the plunger, although not relatively great because this spring at this time is not under compression, nevertheless, is capable of exerting a certain amount of force on the ejecting sleeve.

I think it will be understood, that the magazine is preferably filled to its capacity with the spherical pellets if successive operation of this miniature field piece is to be accomplished without reloading.

To cock this toy cannon prior to the ejecting operation, the cocking lever 72 is depressed, Figure 3, which resultantly rotates the sear support 79 on the axle, the upper end 25 of such support transcribing an arc. This movement is against the action of the spring 70 and it is compressed. When the plunger has moved rearwardly a sufficient distance to uncover the discharge end 48 of the passage 30 47, one of the spherical pellets drops into the inner barrel and rolls rearwardly against the ejecting face of the plunger.

Rearward movement of the sear causes the upturned end 93 thereof to ultimately engage with the ramp 94, and, as the lever 72 is further depressed the rearwardmost end 93 of the sear will also be depressed causing the sear to rotate about its pivotal connection with the sear support. This action will ultimately raise the hook-like end 90 of the sear 35 gradually from engagement with the sear lug of the ejecting sleeve, it being understood, that the hook-like end of the sear has not passed from engagement with the sear lug and is still effective to move the ejecting sleeve in a rearward direction, although only partially in engagement therewith, release of such sleeve not occurring until the rearmost end of the sear reaches the lower end of the ramp.

It is my intention, to so adjust the ejecting mechanism that when the ejecting lever 72 reaches its limit of downward movement, the hook-like end of the sear will pass from engagement with the sear lug to release the ejecting sleeve and plunger and allow them to be snapped forward under the built up tension in the spring 70. As above mentioned, the rearmost end of the sear should, at this time, reach the lowermost end of the lamp, although proper adjustment may be effected to produce the release of the sleeve and plunger prior to the attaining of such position by the rearmost end of the sear. The 40 pellet resting against the forward face of the

plunger will be resultantly forcibly ejected from the muzzle of the gun and the parts of the ejecting mechanism will return to the position shown in Figure 2.

In the return of the sleeve to the position shown in Figure 2, it is arrested in its forward movement by contact of the extension 67 with the transverse bolt 21. The cocking lever 45 may now be released and the spring 31 will operate to return the cocking lever to the position shown in Figure 2. The spring will also move the sear support through a forward arc and the rearmost end 93 of the sear will gradually return to a position above the general plane of the sear under the influence of the 50 torsion spring 91. The hook-like end of this sear will move along the upper surface of the ejecting sleeve until such time is it contacts with and rides up over the sear lug and passes into engagement with the forward side thereof, being forced into such engagement by the 55 torsion spring 91.

One advantageous feature of this invention resides in the fact that the axle of this toy cannon is utilized as a pivot rod for the cocking lever which avoids the necessity for providing an independent fulcrum located at a point remote from such axle as in several prior art devices. By providing a cocking lever that is operatively pivoted on the axle, 60 it has been possible to connect this lever to the ejecting mechanism located within the barrel of the gun, which is also pivotally supported on the axle, in such a manner as to permit of the raising and lowering of the muzzle. Heretofore, it has been relatively impossible 65 to elevate and depress the muzzle of the gun owing to the positional relation existing between the pivot point of the cocking lever and the point or points of support for the barrel. 70

Another advantageous feature of this invention lies in the fact that such parts as the wheels, trail, combined muzzle and dummy recoil cylinder, inner barrel, ejecting sleeve and ejecting plunger are all made up 75 of a light metal first stamped and then bent to proper form with the seams so located as to not interfere with subsequent proper functioning of the various parts when assembled in cooperative relation. Heretofore, the 80 majority of the parts above set out, have been made up of a cast material that was more or less expensive and would not stand up under the rough usage to which the gun was subjected. Furthermore, those elements of 85 the ejecting mechanism that were made up of a stamped material were usually bent to the proper form without regard to the exact location of the seam. Often, in the completed part the seam would be so located as to interfere with the ready progress of the projectiles through the operating mechanism, the 90 seams offering resistance thereto and precluding the free passage thereof. In the 95 present invention, the inventor has paid par-

ticular attention to the allocation of these seams in the completed parts so that the location of such seams would not interfere with passage of the projectiles into the ejecting mechanism.

5. A still further advantageous feature of this invention lies in the fact that the ejecting plunger operates as a valve to allow the entry of only one projectile into ejecting position. Heretofore, the projectiles were stored in a passageway leading to the ejecting chamber that was closed adjacent such ejecting chamber by a butterfly or similar valve. Before a projectile could be introduced into the ejecting mechanism, it was necessary to operate the butterfly to allow the movement of a projectile into ejecting position. Thus, it was necessary to first operate the butterfly and subsequently operate the ejecting mechanism. In this invention, the ejecting plunger serves as a means for admitting projectiles to the ejecting chamber which does away with the necessity for providing a separate valve in the passage leading thereto.

10. 25. A still further advantageous feature of this miniature field piece lies in the fact that it is sturdily built and may be roughly handled without seriously injuring the gun or impairing the efficient operation of the ejecting mechanism.

30. Having thus described my invention what I claim is:

35. 1. A toy gun comprising, an axle, a barrel pivotally mounted on said axle, ejecting mechanism mounted in said barrel, means pivotally mounted on said axle for effecting the operation of said ejecting mechanism, and means for pivotally adjusting said barrel about said axle.

40. 2. In a toy cannon, an exterior housing, an axle on which said housing is pivotally supported and a cocking lever mounted on said axle.

45. 3. A miniature field piece comprising, an axle, means for supporting said axle, a bracket mounted on said axle and adapted to be rotated there around, an exterior barrel rigidly mounted on said bracket, a barrel mounted within said first-named barrel and inclined in a vertical plane upwardly towards the muzzle of said first-named barrel, a feed magazine for conducting projectiles to said second-named barrel formed as a part of said second-named barrel and having its entry located in said first-named barrel, an ejector mechanism mounted in said barrel and means also pivotally mounted on said axle to effect the operation of said ejector.

50. 60. 4. A toy gun comprising an axle, members for supporting said axle, a trail member pivotally mounted on said axle and having a curved surface for contact with a supporting surface, a dummy barrel, a cradle pivotally mounted on said axle and rigidly connected to said barrel for supporting said barrel, and

means mounted on said trail and connected to said barrel for pivotally adjusting said barrel and cradle to said axle as an axis.

5. A toy field piece, comprising, an axle, rotatable members for the support of said axle, a trail member, a dummy barrel mounted on said axle and pivotal thereabout, a cocking lever mounted on said axle and pivotal thereabout simultaneously with said barrel, and means for governing the pivotal movement of said barrel, said means being mounted on said trail and attached to said barrel.

6. A toy field piece comprising an axle, an outer barrel mounted on said axle, an inner barrel, a magazine for conducting projectiles to said inner barrel, a plunger operating in said barrel and adapted to close one end of said magazine, a resilient means for moving said plunger in one direction, means mounted on said inner barrel and connected to said plunger for moving said plunger in a reverse direction, and a cocking means mounted on said axle.

7. A miniature field piece comprising, an outer barrel, an inner barrel, a reciprocating plunger in said inner barrel, resilient means for moving said plunger in one direction and a sleeve for moving said plunger in a reverse direction, said sleeve being mounted on the exterior of said inner barrel, an axle on which said outer barrel is pivotally mounted and a cocking mechanism also mounted on said axle.

8. A toy piece comprising, an axle, an outer barrel mounted on said axle, an inner barrel mounted within said outer barrel, an ejecting plunger mounted within said inner barrel, resilient means for moving said plunger in one direction, means mounted on said barrel for moving said plunger in a reverse direction, said means being actuated by a cocking lever, fulcrumed on said axle.

9. A toy gun comprising an axle, an outer barrel pivotally mounted on said axle, an inner barrel, means for conducting projectiles to said inner barrel, an ejecting plunger within said barrel, means for actuating said plunger comprising a sleeve mounted on and surrounding said inner barrel and axially reciprocable with said plunger with respect to said barrel, manual means to retract said plunger, a spring put under tension by the retractive movement of said plunger, and means to release said plunger from said means when the plunger reaches the limit of its retractive movement.

10. A toy cannon comprising, an axle, means for supporting said axle, an outer barrel pivotally mounted on said axle, an inner barrel, a plunger reciprocating within said inner barrel, a sleeve mounted on said inner barrel, and attached to said plunger, means pivotally mounted on said axle for actuating said sleeve comprising, a sear having one end

engaging with said sleeve and having its opposing end engaging with a ramp.

11. A plunger for a toy gun comprising, a cylindrical body portion and an end face made up of integral segmental sections bent inwardly at right angles to said body portion and provided with an external flange extending longitudinally of said body.

12. In a toy cannon the combination of an outer barrel and dummy recoil cylinder, an inner barrel mounted within said outer barrel and having its axis inclined in a vertical plane upwardly towards the muzzle and relative to axis of said outer barrel, a projectile magazine of substantially uniform diameter, having arcuate ends joined by a substantially straight intermediate portion, the axis of the intermediate portion being disposed in a vertical plane and sloping forwardly and downwardly at an acute angle relative to the axis of the inner barrel, the bore of the magazine being unobstructed to provide for free passage of projectiles to the bore of the inner barrel; a sleeve surrounding said inner barrel and operably mounted thereon in an axial direction, a plunger in rear of said inner barrel operable axially, of substantially the diameter of the inner barrel, a rigid connection between said sleeve and said plunger for the purpose of causing the latter to be operated axially by the former, a spring for operating said sleeve and plunger for the purpose of ejecting the projectiles, means for retracting said plunger and sleeve, means for releasing said sleeve and plunger from the retracting means, means for limiting the forward axial movement of said sleeve and plunger.

13. In a toy cannon, the combination of an outer barrel and dummy recoil cylinder, an inner barrel of substantially uniform bore throughout its length, a projectile magazine having its axis in substantially a vertical plane with the axis of the inner barrel and being of substantially uniform diameter throughout its length and providing an unobstructed passage for projectiles to pass to the barrel, a sleeve surrounding said barrel and rigidly connected to a plunger within said barrel, said plunger projecting into the barrel to prevent entry of projectiles to the barrel except when said plunger is in retracted position, and when in said retracted position to prevent entry to the barrel of more than one projectile at a time, a spring for operating said sleeve and plunger, for the purpose of ejecting the projectiles, means for retracting said plunger and sleeve, means for releasing said sleeve and plunger from the retracting means, means for limiting the forward axial movement of said sleeve and plunger.

14. In a toy cannon, the combination of an outer barrel having an opening through its top near the breech and for the reception of a

projectile magazine and dummy recoil cylinder formed of two sheets of metal pressed into shape and joined together in a vertical plane, the two pressings being substantially symmetrical about the vertical plane of juncture and each pressing forming one-half of the combined outer barrel and dummy recoil cylinder, an inner barrel and projectile magazine formed from one piece of sheet metal blanked out substantially in trident form i. e., as a straight strip of sheet metal to form the barrel and rear extension thereof and having two symmetrically disposed lateral projections one on each side, each to form one-half of the projectile magazine, the whole being pressed so that the lateral arms form semi-circular troughs which, when the straight barrel length is formed around through three hundred and sixty degrees, constitute substantially a curved tubular magazine integral with the barrel, ears formed on the conjuncting edges of the halves of the magazine and lying in the plane of juncture for the purpose of spot welding, a spring operated plunger in the barrel for the purpose of ejecting the projectile, said plunger being rigidly connected to an axially operable sleeve surrounding the inner barrel and formed into circular section from sheet metal and stamped with upwardly projecting ears at its front end and symmetrically disposed about the central vertical plane to form a sear or disengaging edge, a downwardly projecting ear on said sleeve to limit the forward motion of said sleeve when said ear encounters an assembly through-bolt, means for retracting the sleeve and plunger, means for releasing said sleeve and plunger from the retracting means consisting of a pivotally mounted sear, carried by a cocking lever pivoted about the ax'e of the cannon, said sear engaging at its front end the sear edge provided on the axially operable sleeve and its rear end riding on a ramp or incline surface above the projectile magazine, the function of said ramp being to cause disengagement of the sear and sleeve.

15. An ejector for a miniature field piece comprising a blank bent to form a tubular body portion, substantially circular in cross section, and having one end of said tubular body portion closed by a portion of said blank, and the abutting edges of the blank forming said tubular body providing a flange extending longitudinally of said body.

16. A toy field piece comprising a plunger, in combination with a carrier therefor, said carrier comprising a blank bent to form a tubular body portion for a portion of its length, the remainder of said body portion being substantially semi-circular, and means on said body portion for connecting said plunger thereto.

17. A barrel support for a toy cannon comprising a piece of flat stock bent to form a

pair of angularly extending supporting arms formed integrally with an intermediate portion extending at right angles thereto, said supporting arms having barrel embracing portions formed integrally with each outer end thereof, and irremovably secured to the sides of said barrel, an axle on which said support is pivotally mounted, a trail pivotally connected with said axle, and adjustable means between said trail and the rear end of said barrel to adjust the elevation of the discharge end of said barrel.

In testimony whereof, I hereby affix my signature.

WILLIAM L. PAYNE.
